(57) **CLAIM**

The ornamental design for a bag, as shown and described.

DESCRIPTION

FIG. 1 is a top, front, left perspective view of a bag showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of a representative region identified by the number "8" in FIG. 8 thereof.

The broken lines represent features that form no part of the claimed design. The broken lines encircling the portion in FIG. 1 and in the enlarged view of FIG. 8 form no part of the claimed design. The pattern shown in FIG. 8 of the representative region of the bag in FIG. 1 is applied to the exterior surface of the outer shell of the bag in the embodiment shown in FIGS. 1-8.
